LISTING CALCULATOR

Loring Pickering Crosman, Maplewood, N. J., assignor to Gardner Company, Orange, N. J., a corporation of Delaware

Application May 10, 1934, Serial No. 724,891

4 Claims. (CL 197—127)

The invention has relation to paper feed devices, and more particularly to means for quickly and accurately aligning previously printed or typed matter with relation to the printing line of a listing calculator, typewriter or similar machine.

The invention consists in the novel construction and combination of parts, as set forth in the appended claims.

10 In the accompanying drawings illustrating the invention:

Fig. 1 is a front elevation of a record platen, with its associated parts, these parts being shown in the normal positions occupied during the printing or typing operation.

15 Fig. 2 is a similar view, the line finding straightedge being shown in its depressed position.

Fig. 3 is a right end elevation of the platen and associated parts, these parts being in the positions corresponding to those of Fig. 1.

20 Fig. 4 is a similar view, the parts being shown in positions corresponding to Fig. 2.

In these drawings, the numeral 1 designates a cylindrical platen, the journals 2 of which are supported in the framing of a shiftable carriage in the usual manner. Platen 1 may be rotated by the usual knob secured to the journals 2, or by means of a compound lever 3, fulcrumed at 6, upon a sub-frame 7 of the carriage and having a 25 tooth 4 in its upper portion adapted to be engaged with the teeth 5 of a gear mounted upon the stud 6 and meshing with a pinion 8 secured upon the platen. The extent of rotation imparted to the platen by lever 3 may be regulated by means of an adjustable stop 9 engageable with any one of a series of ratchet teeth 10 of the plate 7.

30 Paper to be fed around the platen is placed upon a guide plate 11 and is held for contact 40 with the platen by means of feed rollers 12 forming part of a guiding assembly 13 located below the platen.

A straightedge 14 extends along the face of the platen, being pivotally supported at 15, upon plate 45 16 of the carriage, the points 15 being diametrically opposite the axial point 2 of the platen with relation to the straightedge proper 14. One of the end flanges of straightedge 14 is also provided with a stud 26 engaging a slot in lever 17, 50 fulcrumed at 18 upon the carriage frame, and provided with a cam slotted extension, the walls of which are engaged by a roller 28 mounted in the end of lever 3. Thus, when lever 3 is pulled forward in order to feed paper about the platen, straightedge 14 will be rocked downwardly from

the position shown in Figs. 1 and 3 into that illustrated in Figs. 2 and 4.

Owing to the relation of pivot point 15 to the axis 2 of the platen, the above-described movement of straightedge 14 will carry the lower edge thereof outwardly away from the face of the platen, opening up a space through which the paper will be fed, while the upper face of the straightedge will be brought close to the face of the platen, so that any type characters upon the paper may be readily located relative to the printing line. That is to say, the straightedge is designed to have two line indicating edges, the lower edge normally lying immediately above the last completed line on the paper sheet, and the upper edge being brought when the straight edge is in lowered position opposite a line on the platen immediately below the figures of a line which has been partially typed.

In Fig. 1 an upper completed line of tabulated figures is represented at 19, and an incomplete line of tabulated figures at 20. Alignment of the last completed line with relation to the straight edge as indicated in Fig. 1, will therefore, bring the paper into position for printing upon the next lower line. Assuming, however, that a partially completed line 20 is to receive additional entries thereon, such partially printed line may be very accurately brought to the printing line by comparison with the upper face of straightedge 14, 30 in the manner shown in Fig. 2. This may be secured by pulling down the straightedge after the paper has been inserted, roller 18 moving idly in the slot of lever 17 during this adjustment. The paper being thus aligned in the position in 35 which it is to be printed, that is to say, no subsequent line spacing being necessary, a very accurate alignment may be made.

The member 14 has been termed a straightedge, because of its utility in connection with line finding. Independently of this function, however, member 14 is useful as a paper guide, serving to hold the upper portion of the paper sheet toward the rear, and owing to its pivotal character and movement toward the guide 13 providing for proper feeding of the paper. That is to say that during the feeding of the paper, the device is positioned as a part of the paper guide, while during the printing operation the device holds the upper edge of the paper rearwardly, 45 without extending at any point across the printing line.

I claim:

1. In a paper feed device, the combination with a cylindrical platen, of a straightedge extending 55

along the face of and pivoted at the opposite side of said platen, and means for rocking said straightedge, adapted to bring one edge and the opposite edge thereof alternately close to said platen.

5. 2. In a paper feed device for sheets of printed matter, the combination with a cylindrical platen, of a straightedge extending along the face of said platen and mounted for reciprocatory movement, 10 and means for reciprocating said straightedge, adapted to bring one edge and the opposite edge thereof alternately close to said platen at different radial points, to indicate the relation of two adjacent lines of printed matter to the new printing line.

15. 3. In a paper feed device, the combination with a cylindrical platen and an adjacent paper guide, of a strip metal straightedge extending along the face of and pivoted eccentrically of the axis of

said platen, and means operable to rotate said platen and to rock said straightedge in a direction opposite to such rotation, adapted to move an edge of said straightedge in a substantially tangential path with relation to and away from said platen and into proximity to said paper guide to form a continuation thereof.

4. In a paper feed device, the combination with a cylindrical platen and an adjacent paper guide located below the printing line, of a pivotally mounted strip metal straightedge normally extending along the face of the platen above the printing line, and means operable to rotate said platen and to rock said straightedge in a direction opposite to such rotation and into proximity 10 to said paper guide to form a continuation thereof. 15

LORING PICKERING CROSMAN.
